UNITED STATES PATENT OFFICE.

LYLE BEEMAN, OF MILWAUKEE, WISCONSIN.

AUTOMATIC SIGN.

1,313,159.

Specification of Letters Patent. Patented Aug. 12, 1919.

Application filed January 14, 1915. Serial No. 2,127.

To all whom it may concern:

Be it known that I, LYLE BEEMAN, a citizen of the United States, and resident of Milwaukee, in the county of Milwaukee and State of Wisconsin, have invented new and useful Improvements in Automatic Signs, of which the following is a description; reference being had to the accompanying drawings, which are a part of this specification.

10 This invention has for its object to provide an automatic sign driven by a suitable motor to change the reading matter of the sign at regular intervals by presenting a series of sign plates successively to view, each 15 sign plate being automatically withdrawn as the succeeding sign plate is brought to view, and the feeding movements of the sign plates in one part of their circuit of travel through the machine producing the 20 operation of mechanism for controlling and effecting their movements during the remainder of their circuit of travel.

Another object of the invention is to provide an automatic sign in which the sign 25 plates are elevated by motor driven mechanism and during their upward travel first effect the raising of a pair of swinging arms to a position to take another sign plate from its elevated position and then restrain the 30 return downward movement of said swinging arms to the position for transferring the sign plate carried thereby to holders for exhibiting the sign plate, such holders being so mounted and arranged as to discharge the 35 sign plate held thereby on the approach of the swinging arms.

Another object of the invention is to provide automatically operated escapement means actuated by the other parts for assuring 40 the sign plates moving singly, though permitting a surplus number of sign plates in the circuit of travel to increase the number of changes in the reading of the sign.

Another object of the invention is to provide 45 such a sign with sign plates having translucent characters illuminated by electric lamps within the sign casing, said lamps being preferably automatically controlled to flash only during the time that the sign 50 plates remain stationary in their exposed position and being extinguished during the operation of changing the sign plates.

Another object of the invention is to perfect details of construction of automatic signs of this type. 55

With the above and other objects in view the invention consists in the automatic sign as herein claimed and all equivalents.

Referring to the accompanying drawings in which like characters of reference indicate the same parts in the different views:

Figure 1 is a vertical transverse sectional view of an automatic sign constructed in accordance with this invention and being approximately on the plane of line 1—1 of Fig. 4, with parts in the position in which the swinging arms have taken the sign plate and are about to swing downwardly therewith;

Fig. 2 is a similar view thereof on the plane of line 2—2 of Fig. 5 with the swinging arms in intermediate position during their lowering movement, the exposed sign plate having been discharged by the rocking sign holders; 75

Fig. 3 is a similar view on the plane of line 3—3 of Fig. 4 with the swinging arms in their lowermost position after having discharged the sign plate onto the sign holders;

Fig. 4 is a sectional plan view of the left-hand end of the automatic sign on the plane of line 4—4 of Fig. 2; 80

Fig. 5 is a similar view of the right-hand end of the automatic sign on the plane of line 5—5 of Fig. 3; 85

Fig. 6 is a sectional elevation showing parts at the upper rear corner of the device;

Fig. 7 is a detail view of a portion of one of the sign plate frames; 90

Fig. 8 is a sectional detail view of one of the sign rests on the plane of line 8—8 of Fig. 3;

Fig. 9 is a front elevation of the sign showing the stationary and movable sign plates as exposed to view; and, 95

Fig. 10 is a detail view showing the crank for moving the sign lifting slide.

In these drawings 15 indicates a suitable casing which has a glass covered open front 100 16 behind which appear sign plates 17 and 18, the former being stationary, and the latter being automatically replaced with others during the operation of the device. Both

sign plates are preferably formed of grooved frames 19 containing removable character strips 20 of fiber or other suitable opaque material having the letters or other sign characters cut therein and backed with a covering of tracing linen or other suitable translucent material. These character strips are held within the grooved upper and lower edges of the frames and the frames are braced at intervals by narrow spring strips 21 connecting said upper and lower grooved edges, said bracing strips being so narrow, and being arched rearwardly as to not interfere with the light showing through the sign characters. At the ends of the sign plate frames 19, slightly above the center thereof, are projecting lugs or trunnions 22 by means of which the sign plates are supported and conveyed from one position to another, the stationary sign plate 17 having its trunnions 22 removably fitting upon suitable hooks 23 by which it is held in position.

The hinged cover 24 of the casing carries an electric motor 25, the speed of which is controlled by a suitable rheostat 26 within the casing having an operating handle 27 projecting through a slot thereof so as to be operated from the outside. A suitably mounted grooved pulley 28 is driven by a belt 29 connecting it with the motor 25 and carries a worm 30 meshing with a worm wheel 31 to drive a horizontal shaft 32 extending the full length of the casing and journaled in the ends thereof. Near the ends of shaft 32 are worms 33 which mesh with worm wheels 34 on vertical tubular shafts 35. The shafts 35 have plugs 36 in their lower ends resting on balls 37 contained in step bearings 38 secured to the ends of the casing, and openings through the plugs admit oil from the interior of the tubular shafts to the step bearings. At their upper ends the shafts 35 are journaled in bearings in the bottom of oil cups 39 which project from the ends of the casing. An opening in the bottom of each oil cup 39 admits oil to the interior of the vertical shafts 35 to lubricate the upper and lower bearings thereof. Each vertical shaft 35 is surrounded by a helix 40 which may be formed thereon as a thread on a screw but which is preferably made by fitting a coil spring around the shaft and securing it thereto, the purpose of this helix being to form together with stationary vertical guides 41 an elevating screw conveyer for lifting the sign plates by means of their trunnions 22 which fit between the edge of the vertical guide 41 and the shaft 35 and between the convolutions of the helix. The edge of the vertical guide 41 is rabbeted to form a guide shoulder against which the ends of the trunnions 22 abut for holding the sign plate against longitudinal movement during its upward

travel. The worms 33 are of opposite pitch, 65 that is, one is a right-hand worm and the other is a left-hand worm, so that the shafts 35 are driven in opposite directions and the helixes are right and left hand and are provided with lugs 42 near their upper ends 70 which serve to force the trunnions 22 forwardly onto inclined projections 43 at the upper ends of the vertical guides 41. A double toothed dog 44 is pivotally mounted in a slot of each of the inclined projections 43 75 and is pressed forwardly by a spring 45 to a position in which one of its teeth is engaged by the trunnion 22 of the end sign plate, thus serving to prevent the sign plates falling off of the projections. These dogs constitute escapement means for releasing the end sign plates when they are forced rearwardly against the pressure of their springs 45 by means to be now described without allowing other sign plates to fall off of their support.

A shaft 46 is journaled in the ends of the casing and has a cam blade 47 fixed thereon close to one of the elevating screws and in the path of travel of the trunnions 90 22 at one end of the sign plates so as to be lifted thereby as each sign plate travels upwardly, and swinging arms 48 fixed on the shaft 46 near its end are raised by this movement of said shaft from the position 95 shown in Fig. 3 to the position shown in Fig. 1. These swinging arms 48, as best seen in Figs. 4 and 6, pass through slots 49 in the vertical guides 41 and have their ends offset inwardly to lie in the plane of travel of the trunnions 22 of the sign plates, and form hooks 50 to receive the trunnions of the end sign plate on the projections 43 when the double toothed dogs 44 are swung by the swinging arms to release them. The offset portions of the swinging arms have notches 51 to receive the lower ends of the double toothed dogs 44 and the dogs are swung when the ends of these notches engage therewith as shown in Fig. 1. As the trunnion 22 which has lifted the swinging arms passes the rounded nose of the cam plate 47 the weight of the arms 48 and the sign plate supported thereby is sufficient to cause said arms to descend, turning the shaft 46 and 105 swinging the cam plate 47, but such descent is restrained by the engagement of the eccentric outer edge of the cam plate 47 remaining in bearing contact with the trunnion, and in order that this restraint may continue throughout the downward movement of the swinging arms said cam plate is provided with an extension leaf 52 continuing the eccentric curvature of the cam plate. In order that the swinging movements of the cam plate 47 with its extension leaf 52 may not make it necessary to increase the depth of the casing such ex-

tension leaf is pivotally mounted on the cam plate at 53 so as to fold therewith as a collapsible cam, a stop pin 54 being provided on the cam plate to be engaged by the 5 extension leaf to limit its swinging movements with respect to the cam plate, and a coil spring 55 connecting said extension leaf with the rear wall of the casing serving to hold it in such engagement except when 10 folded or partly folded at which times the extension leaf bears against the rear wall of the casing. Pivotally mounted to the ends of the casing near the front wall thereof are levers 56 which stand 15 in the path of travel of the offset portions of the swinging arms 48 to be engaged thereby and swung downwardly against the pull of springs 57 which tend to hold them in their upper position. Rollers 58 on the levers 56 20 are adapted in the downward movement of said levers to engage the upper ends of push rods 59 which are carried by the front ends of rocking levers 60 fulcrumed to the end walls of the casing, said push rods near their 25 upper ends being guided by slotted stationary guides 61 projecting from the end walls of the casing, and the play of the push rods in such slotted guides being sufficient to permit the push rods to be forced upwardly by 30 leaf springs 62 bearing against their lower ends as soon as the rollers have depressed said push rods and have passed over the ends thereof in about the position of the parts shown in Fig. 2. Sign holder plates 35 63 are fulcrumed at 64 on studs 65 projecting from the end walls of the casing and are pivotally connected at 66 to the push rods 59 so as to be swung with the depression of said push rods from a normal position, 40 as shown in Fig. 1, to a position as shown in Fig. 2 to turn the angular notches thereof so that their rear edges are inclined rearwardly, and thus discharge by gravity the sign plate which has had its trunnions 22 45 placed in said notches when in their normal position by the descending swinging arms 48, such notched plates constituting the rocking sign holders previously referred to. The transfer of the sign plate trunnions from 50 the hook shaped ends of the swinging arms 48 to the notches of the rocking sign holders takes place just before the end of the downward movement of the swinging arms, when the trunnions engage the rear edges of the 55 notches which are then inclined forwardly, the weight of the sign thus being taken by the sign holders, and the sign plate sliding forwardly into the crotches of the notches where the sign is held in its exposed or 60 display position just behind the glass front 16.

When the sign is discharged from the sign holders 63 by the downward movement of the push rods 59, as just described, the trunnions thereof slide off of the rear edges

of the notches onto inclined guide ledges 67 65 which project from the end walls of the casing the sign is centered to correct endwise displacement by a beveled or inclined guide surface 68 above the ledge 67. The inclined ledges 67 carry the sign rearwardly toward 70 the elevating conveyors, but their incline is preferably made in two steps, as shown, with a raised portion between them to form a pocket 69 or intermediate position of rest to shorten the distance of travel of the sign 75 which is discharged by the sign holders and give it an opportunity to cease its swinging movements which it may have acquired as the result of its quick rearward descent. Before the trunnions of the sign reach the 80 pockets 69 they are arrested by engaging the pointed upper ends of slides 70 which are vertically movable through grooves in the ledges 67 and also through guides 71 projecting from the end walls of the casing, being 85 raised and lowered by having pivotal connection with the rocking levers 60 before mentioned. The slides 70 are in their raised position as shown in Fig. 2 at the time the push rods 59 are depressed by the levers 56, 90 and engage the trunnions of the sign plate discharged by the sign holders 63, but when the push rods are released and are forced upwardly by their springs 62 said slides are withdrawn so that the trunnions rest in the 95 pockets 69 of ledges 67, as shown in Figs. 1 and 3. On the succeeding upward movement of the slides their inclined upper edges act as cams for forcing the trunnions over the raised portion of the ledges 67 so that they 100 slide farther down the incline where a number of the sign plates may be grouped for successive admission to the elevating conveyors.

An escapement slide 72 is mounted in 105 guides 73 projecting from the end wall of the casing at each end of the machine and has a forwardly projecting upturned V-shaped escapement arm 74 to be moved vertically into and out of the path of the trunnions 22 on the ledges 67, such vertical movements of the escapement slides being accomplished by a link 75 connecting one of said escapement slides with the cam plate 47 at one end of the machine and by a similar 110 link connecting the other escapement slide with a crank arm 76 on shaft 46 at the other end of the machine. The upward movement of the cam plate 47 caused by the engagement therewith of the trunnion of the 115 sign plate during its upward travel, as before described, causes the lifting of the escapement slides 72 from the position shown in Fig. 3 where the hooked end thereof lies beneath the trunnions of the end sign plate 120 to the raised position shown in Fig. 1, thus lifting said trunnions into engagement with the lower end of the worm or screw thread 125

40 to start the sign plate in its upward travel, said hooked ends of the escapement slides while in their raised position holding back the trunnions of the other sign plates
 5 which are resting on the ledges 67, and only permitting their farther downward movement to present the trunnions of the next sign plate in position to be engaged when the escapement slides are lowered to the position shown in Fig. 3.

The operation of the automatic sign of this invention has been particularly described incidental to the description of the construction and arrangement of parts there-
 15 of but may be briefly summarized as follows: The swinging arms 46 are raised by the turning of shaft 46 incident to the lifting of cam plate 47 by the trunnion of an ascending sign plate until the hooks 50 at their
 20 ends engage the trunnions of the end sign plate supported by projections 43 of the stationary guides, at which time the double toothed dog 44 has been swung to release the trunnions of such end sign plate, so that
 25 during the following downward movement of the swinging arms 48 this sign plate is lowered thereby, the lowering movements being restrained by the cam surface of cam plate 47 and its extension leaf 52 bearing
 30 against the trunnions of such ascending sign plate. When the descending sign plate is in an intermediate position the sign plate being displayed and supported on the sign holders 63 is discharged rearwardly by the
 35 lever 56 depressing the push rods 59, the sign holders immediately returning by the escape of the push rods from the rollers of levers 56 so as to be in position to receive the descending sign from the hooks of the
 40 swinging arms 48 just before the latter reach the end of their downward movement, the sign plate so deposited on the sign holders assuming the position of display behind the glass front of the sign casing and remaining
 45 in this position until discharged rearwardly by the rocking of the sign holders incident to the succeeding downward movement of the swinging arms 48 in lowering the next sign plate into position. When discharged
 50 from the sign holders the sign plate takes its place in line with the series of sign plates supported on the inclined ledges 67 though pausing momentarily with its trunnions resting in the pockets 69 until forced over
 55 the raised portion of the ledges by the upward movement of the slide 70. When its next turn for elevation arrives the sign plate is lifted by the engagement of the escapement slides 72 with its trunnions and is carried into engagement with the rotating worm conveyers to repeat the cycle of operation.

Electric light bulbs 77 may be suitably positioned within the sign casing so as to

illuminate both the stationary sign 17 and 65 the changeable sign 18 and preferably a suitable switch mechanism 78 having connection with a crank arm 79 on the rock shaft 46 is provided for controlling the supply of current to the lamp bulbs 77 to cause 70 an intermittent burning thereof so that the signs are lighted while the changeable signs remain stationary in their exposed position, the lamps being extinguished during the short interval required for automatic substitution of one sign plate for the other. 75

By means of this invention the reading of the sign may be automatically changed in a continuous operation, one movable sign plate after another appearing to view to be 80 read in conjunction with the stationary sign plate and being illuminated from within without showing the substitution of one movable sign plate for another by the illuminating lamps being automatically extinguished at such times. The mechanism has a capacity for a number of sign plates in order that the changes may be numerous and the sign interesting, the various escapement means assuring the maintenance of 90 proper order in the movements of the sign plates so that the operation may be continuous as long as the motor is kept in operation.

What I claim as new and desire to secure 95 by Letters Patent is:

1. An automatically changeable sign, comprising a casing having a sign opening, means for supporting signs behind the sign opening, sign plates for successively resting 100 on the supporting means, means for discharging the sign plates from the supporting means, means for conducting the sign plates rearwardly, elevating means for lifting the sign plates successively, and swinging arms for lowering the sign plates from the elevating means to the supporting means.

2. An automatically changeable sign, comprising a casing having a sign opening, 110 means for supporting sign plates behind the sign opening, sign plates for successively resting on the supporting means, means for conducting the sign plates rearwardly from the supporting means, elevating means for 115 lifting the sign plates successively, and means operated by the ascending sign plates for lowering the sign plates from the elevating means to the supporting means.

3. An automatically changeable sign, comprising a casing having a sign opening, means for supporting sign plates behind the sign opening, sign plates for successively resting on the supporting means, an inclined guide for conducting the sign plates from 125 the supporting means, elevating means for lifting the sign plates successively, and means operated by the ascending sign plates

for lowering the sign plates from the elevating means to the supporting means and for simultaneously moving the supporting means to discharge sign plates therefrom.

5 4. An automatically changeable sign, comprising a casing having a sign opening, means for supporting sign plates behind the sign opening, sign plates for successively resting on the supporting means, an inclined 10 guide for conducting the sign plates from the supporting means, elevating means for lifting the sign plates successively, swinging arms for lowering the sign plates from the elevating means to the supporting means, 15 and means in the path of the ascending sign plates for lifting the swinging arms and for restraining the downward movement thereof.

5 5. An automatically changeable sign, comprising a casing having a sign opening, 20 means for supporting sign plates behind the sign opening, sign plates for successively resting on the supporting means, an inclined guide for leading sign plates away from the supporting means, elevating means comprising a screw conveyer for lifting the sign plates successively, means for lowering the sign plates from the elevating means to the supporting means, and means in the path of 25 the ascending sign plates to be engaged thereby for lifting sign plates from the inclined guide to the elevating means.

6. An automatically changeable sign, comprising a casing having a sign opening, 30 means for supporting sign plates behind the sign opening, sign plates for successively resting on the supporting means, an inclined guide for leading sign plates away from the supporting means, elevating means for lifting the sign plates successively, swinging arms for lowering the sign plates from the elevating means to the supporting means, and means projecting into the path of the 35 ascending sign plates for moving the swinging arms.

45 7. In an automatic sign, an elevating conveyer comprising a pair of suitably driven worm shafts, stationary guides parallel thereto, and sign plates having projecting 50 trunnions extending between the guides and the worm shafts and between the convolutions of the worms to be elevated by the turning of the worm shafts, the movement of the bearing surfaces of the worms on 55 which the trunnions rest being longitudinal of the trunnions.

55 8. In an automatic sign, an elevating conveyer comprising a pair of suitably driven shafts having screw threads, stationary 60 guides parallel with the shafts, sign plates having projecting lugs at their ends fitting between the shafts and the guides and between the screw threads of the shafts to be elevated by the turning of the shafts, the

movement of the bearing surface of the 65 screw threads on which the lugs rest being longitudinal of the sign frame.

9. In an automatic sign, an elevating conveyer comprising suitably driven shafts having helically wound threads thereon, stationary guides positioned adjacent to the shafts and parallel therewith and having rabbeted edges to form guide ways with the shafts, and sign plates with lugs projecting from their ends to fit within said guide ways 70 between the convolutions of the helical threads and in end abutment with the stationary guides to be lifted by the turning of the shafts, the movement of the bearing surfaces of the threads on which the lugs 75 rest being longitudinal of the sign plates.

10. An automatically changeable sign, comprising a casing having a sign opening, means for supporting sign plates behind the sign opening, sign plates for successively 80 resting on the supporting means, means for removing the sign plates from the supporting means, an elevating conveyer for lifting the sign plates successively, swinging arms for lowering the sign plates from the elevating means to the supporting means, and an arm connected with the swinging arms 85 and projecting into the path of the ascending sign plates to be moved thereby for lifting the swinging arms and provided with a cam extension for remaining in contact with the ascending sign plate to retard the 90 downward movement of the swinging arms.

11. An automatically changeable sign, comprising a casing having a sign opening, 100 means for supporting sign plates behind the sign opening, sign plates for successively resting on the supporting means, means for removing the sign plates from the supporting means, elevating means for lifting the sign plates, swinging arms for lowering the sign plates from the elevating means to the supporting means, an arm connected with the swinging arms and standing in the path of the ascending sign plates 105 to be lifted thereby for lifting the swinging arms, and a spring retracted cam shaped extension leaf having a limited pivotal movement on the arm for remaining in engagement with the ascending sign plate to 110 restrain the downward movements of the swinging arms.

12. An automatically changeable sign, comprising a casing having a sign opening, means for supporting sign plates behind the sign opening, sign plates for successively resting on the supporting means, means for removing the sign plates from the supporting means, an elevating means for lifting the sign plates successively, swinging arms for 120 lowering the sign plates from the elevating means to the supporting means, an arm connected with the swinging arms and project- 125

ing into the path of the ascending sign plates to be lifted thereby for raising the swinging arms, and means for retarding the downward movements of the swinging arms.

13. An automatically changeable sign, comprising a casing having a sign opening, means for supporting sign plates behind the sign opening, sign plates for successively resting on the supporting means, means for removing the sign plates from the supporting means, elevating means for lifting the sign plates successively, an elevated, inclined support receiving the sign plates from the elevating means, sign lowering means for carrying the signs from the elevated support to the supporting means, and escapement means on the elevated support operated by the sign lowering means for releasing the sign plates singly from the elevated support.

14. An automatically changeable sign, comprising a casing having a sign opening, means for supporting sign plates behind the sign opening, sign plates for successively resting on the supporting means and having projecting lugs at their ends by which they are supported, means for conducting the sign plates from the supporting means, an elevating conveyer for lifting the sign plates successively by their lugs, an elevated inclined support receiving the lugs of the sign plates from the elevating conveyer, suitably operated swinging arms for lowering the sign plates from the elevated support to the other supporting means, and double toothed dogs on the elevated support engaged by the swinging arms for releasing the sign plates singly.

15. An automatically changeable sign, comprising a casing having a sign opening, pivotally mounted sign supports for holding the sign plates behind the sign opening, sign plates for successively resting on the supporting means and having projecting lugs at their ends by means of which they are supported, an inclined guide for leading the sign plates away from the sign supports, an elevating conveyer for lifting the sign plates successively, swinging arms for lowering the sign plates to the sign supports, and means operated by the downward movement of the swinging arms for rocking the sign supports to discharge the sign therefrom onto the inclined guide.

16. An automatically changeable sign, comprising a casing having a sign opening, pivotally mounted sign supports for holding the sign plates behind the sign opening, sign plates for successively resting on the sign supports and having projecting lugs at their ends by means of which they are supported, an inclined guide for leading the sign plates away from the sign supports, an elevating

conveyer for lifting the sign plates successively, swinging arms for lowering the sign plates to the sign supports, spring pressed push rods connected with the sign supports, levers engaging the push rods and standing in the path of the swinging arms to be moved thereby for swinging the sign supports to discharge the sign plate therefrom onto the inclined guides on the downward movement of the swinging arms.

17. An automatically changeable sign, comprising a casing having a sign opening, pivotally mounted sign supports for holding the sign plates behind the sign opening, sign plates for successively resting on the sign supports and having projecting lugs at their ends by means of which they are supported, an inclined guide for leading the sign plates away from the sign supports, an elevating conveyer for lifting the sign plates successively, swinging arms for lowering the sign plates to the sign supports, spring pressed push rods connected with the sign supports, spring retracted levers in the path of the swinging arms to be moved thereby, and rollers on the levers engaging the push rods for swinging the sign supports on the downward movement of the swinging arms to discharge the sign plate therefrom onto the inclined guide, said rollers passing over the ends of the push rods and permitting the return of the sign supports before the swinging arms complete their downward movement.

18. An automatically changeable sign, comprising a casing having a sign opening, means for supporting sign plates behind the sign opening, sign plates for successively resting on the supporting means and having projecting lugs at their ends by which they are supported, means for discharging the sign plates from the supporting means, inclined guide ledges receiving the lugs of the sign plates as they leave the supporting means, said inclined guide ledges having a raised intermediate portion forming a pocket, suitably operated slides having cam edges for engaging the lugs of the sign plates and moving them out of the pockets of the guide ledges, an elevating conveyer for lifting the sign plates, and means for lowering the sign plates onto the supporting means.

19. An automatically changeable sign, comprising a casing having a sign opening, pivotally mounted sign supports for holding sign plates behind the sign opening, sign plates for successively resting on the sign supports and having projecting lugs at their ends by which they are supported, inclined guide ledges to receive the lugs of the sign plates as they leave the sign supports, said guide ledges having raised intermediate

portions forming pockets to retain the lugs of the sign plates, slides having inclined edges for engaging the lugs of the sign plates for forcing them out of the pockets,
5 an elevating conveyer for lifting the sign plates, swinging arms for lowering the sign plates to the sign supports, spring pressed push rods connected with the sign supports and operated by the downward movements
10 of the swinging arms to rock the sign sup-

ports to discharge the sign plate therefrom, and a lever connecting the push rods with the slides.

In testimony whereof I affix my signature in presence of two witnesses.

LYLE BEEMAN.
